United States Patent Office.

GEORGE L. WITSIL, OF PHILADELPHIA, PENNSYLVANIA.

Letters Patent No. 97,019, dated November 16, 1869.

IMPROVED DEVICE FOR GRATING GREEN CORN FROM THE COB, &c.

The Schedule referred to in these Letters Patent and making part of the same.

To all whom it may concern:

Be it known that I, GEORGE L. WITSIL, of Philadelphia, in the county of Philadelphia, and State of Pennsylvania, have invented a new and useful Improvement in Devices for Grating or Removing Green Corn from the Cob, and for other purposes; and I do hereby declare that the following is a full, clear, and exact description thereof, reference being had to the accompanying drawings, and to the letters of reference marked thereon.

Figure 1 is a plan or top view of my improved device, showing the apertures through the metal plates, and their position with reference to each other.

Figure 2 is a transverse section on line $x x$ of fig. 1.

Figure 3 is a similar view, showing the metal plate as secured to two bars, for the purpose of leaving the bottom open.

Figure 4 is a bottom view of the frame or bed to which the plate is to be attached when its bottom portion is to be left open, as in fig. 3.

Figure 5 is a longitudinal vertical section on line $y y$ of fig. 1.

Corresponding letters refer to corresponding parts in the several figures.

This invention relates to that class of devices which is used for removing green corn from its cob, for table-use, or for any other purpose, but which may be used for various other purposes, such as grating various substances, sharpening pencils, &c.; and

It consists in the construction of such devices, as will be more fully explained hereinafter.

A, in the drawings, represents what may be a block or piece of wood, metal, ivory, rubber, or any other suitable substance, with a semicircular or other-shaped groove, formed longitudinally upon one of its surfaces, as shown in fig. 2; or it may be two bars of any of the above-named or any other suitable material, which will serve as a bed for the metal plate, hereafter to be described, to rest upon.

The object of the groove or space in the centre of the bed is to provide a space for the material which is removed from the article which is grated and cut to fall into.

B B represent a plate of steel, iron, or of suitable material, which is to be secured to the bed by means of screws, as at $a a$, fig. 1.

This plate is to be bent into a form similar to that shown in figs. 2 and 3, or so as to have upon its sides two parallel surfaces, for securing it to its bed, while its central portion is to be bent downward, so that for a portion of the distance the sides of the depressed portion shall form an acute angle with reference to

each other, while lower portions of the depression, or that portion of the plate which extends below such angle, may be brought together, and thus be made to assume a vertical position.

It will be apparent, however, that if preferred, this plate may be made of two distinct pieces of metal, bent as above described, so as to form the proper angles, and also the vertical portions, and be riveted or screwed together at the bottom, or through the vertical portions of such plates.

Those portions of this plate, or of these plates, which present their surfaces at an angle to each other, are to be provided with slots, arranged as shown in fig. 1, so that as any instrument or thing is drawn through or between them, two cutting-edges shall be presented, and thus it be adapted to the uses above stated.

In cutting or punching these slots, the instrument for that purpose should be placed upon the under or outer side of the plate, in order that the projections raised by such cutting or punching may be upon the inner or upper surface thereof, for the purpose of forming the cutting or grating-surfaces upon such plate or plates.

When this instrument is to be used as a grater, or for removing corn from its cob, its plate or plates B B may be made of steel, or of heavy tin plates, or of any other metal sufficiently hard to resist the wearing-action of any substance to be acted upon. Under such circumstances, the cutting or punching of the slots will form upon the projections a surface sufficiently sharp for such purposes; but when it is to be used as a pencil-sharpener, or for any other purpose requiring a cutting-edge, such edge may be formed upon plates of steel, which alone would be used in such cases, because of its better adaptation for the purpose, by grinding with a stone fitted to the space between the angular sides of the plates, or by filing the same with a common file.

Having thus described my invention,

What I claim, and desire to secure by Letters Patent, is—

The within-described grater or cutter, consisting of the bed A and plate or plates B, with the apertures therein cut at an acute angle, substantially as and for the purpose set forth.

In testimony whereof, I have signed my name to this specification, in the presence of two subscribing witnesses.

GEO. L. WITSIL.
